Henry F. Shaw.

UNITED STATES PATENT OFFICE.

HENRY F. SHAW, OF BOSTON, MASSACHUSETTS.

SLIDE-VALVE.

SPECIFICATION forming part of Letters Patent No. 292,261, dated January 22, 1884.

Application filed June 14, 1883. (No model.)

To all whom it may concern:

Be it known that I, HENRY F. SHAW, a citizen of the United States, residing at Boston, in the county of Suffolk and State of Massachusetts, have invented certain new and useful Improvements in Slide-Valves, of which the following is a specification, reference being had to the accompanying drawings.

The object of my invention is to produce a slide-valve which shall provide, at the instant of opening a port, a greater opening for the passage of steam than is done by means of the ordinary slide-valve, and also to produce a combined valve adapted for two cylinders having pistons plying therein in opposite directions, said valve being constructed to provide, particularly, free and unobstructed exhaust-passages.

My invention consists in so forming the sides or edges of the openings of the valve and valve-seat that the open passages will be irregular or zigzag in shape, in distinction from openings having their longitudinal sides rectilinear; and, also, in the combination of a **B**-valve and **D**-valve joined together to be operated as one valve with the valve-seat, the valve and valve-seat having steam-passages formed and located with reference to each other as hereinafter set forth.

In the drawings, Figures 1 and 2 are plan views of a valve and valve-seat embodying my invention, the valve being shown in two different positions on the seat. Fig. 3 is a plan view of the seat, the valve having been removed. Fig. 4 is an outline of the face of the valve. Fig. 5 is a section of valve and valve-seat on line 1 1; and Fig. 6, a section of valve and valve-seat on line 2 2 in Figs. 3 and 4, the valve being in the position on the seat as illustrated in Fig. 1. Fig. 7 is a diagram for more particular reference hereinafter.

The valve-seat A has a port, *a*, to lead to one end of one of two cylinders, a port, *b*, to lead to the opposite end of the same cylinder, a port, *c*, leading to one end of the other of the two cylinders, and a port, *d*, leading to the opposite end of the latter cylinder. There is a common exhaust port and passage, *e*, through the length of the seat. The cylinders are supposed to be located side by side, and the valve and valve-seat over the space between the cylinders, or over the adjoining

sides of the same, the face of the seat and valve being thus brought into a horizontal plane, though the cylinders may be one above the other, so that the face of the valve and valve-seat will be in a vertical or inclined plane. That part of the valve B which corresponds to a **D**-valve has an opening, *f*, in its face, leading to an exhaust-chamber, *g*, through which the steam passes from either of the ports *a* and *b* to the exhaust-port *e*. That part of the valve B which corresponds to a **B**-valve has openings *h* and *i* in its face, leading to a chamber, *j*, in the valve, through which live steam passes from the steam-chest to the port *c*, and exhaust-steam from the port *c* to the exhaust-port *e*, and has openings *k* and *l* in its face, leading to a chamber, *m*, in the valve, through which live steam passes from the steam-chest to the port *d*, and exhaust-steam from the port *d* to the exhaust-port *e*. Live steam enters the port *a* above the seat at and opposite the edge *n* of the valve, and the port *b* at and opposite the edge *o* of the valve. Live steam enters the opening *h* under the valve at and opposite the edge *p* of the seat, and the opening *l* at and opposite the edge *q* of the seat. The inner longitudinal edges and edge faces of the sides of the ports *a* and *b*, opening *f*, openings *h* and *l*, and outer longitudinal edges and edge faces of the sides of the ports *c* and *d* are grooved, whereby there are formed grooves *r* and projections *s* at the above-named edges and edge faces of the valve, and grooves *t* and projections *u* at the named edges and edge faces of the valve-seat. Said edges are at the sides of the passages formed in the working of the valve for the exhaust-steam to the chambers in the valve. Each projection on the valve is opposite a groove in the seat, and consequently each projection on the seat is opposite a groove in the valve, and the projections and grooves have a like contour, so that an opening between two edges so formed has a shape represented at *v* in Fig. 7. Through such an opening, especially when the zigzag passage is of slight width, as it is at the commencement of making the same, I believe more steam will pass than through a straight passage—that is, one having rectilinear sides.

I do not confine this part of my invention to any particular form of projections and grooves, since the effect desired will be produced in a

degree whatever the form of projections and grooves may be, provided they correspond to each other.

In the drawings is illustrated provision for this irregular or zigzag passage for the exhaust only; but such may also be employed for the live steam.

It will be seen that when the exhaust-steam is about to be admitted to either of the chambers *j* and *m*, and either of the ports *c* and *d* is about to be opened, the corresponding opening, *i* or *k*, in the valve is well over the exhaust-port *e*. This is an important feature in my invention, since the flow of the exhaust-steam is not retarded, as it would be were the passages from said chambers to the common exhaust-port, *e*, opened at the same time that the ports *c* and *d* were opened. By this arrangement of the passages and construction of this part of the valve, as shown, I provide for ample "lead" in the part of the valve corresponding to a **B**-valve for the exhaust-steam, and very free passage for the egress of the same.

25 I claim as my invention—
1. In a slide-valve and seat therefor, openings the sides of which have projections and grooves in their edges or edge faces, whereby one or more passages across the plane of contact of the valve and valve-seat are irregular or zigzag in shape, substantially as specified.

30 2. In combination with the chambers *j* and

m, openings *h* *i* and *k* *l* in the valve, and ports *c*, *d*, and *e* in the seat, said openings and ports being so located with reference to each other 35 that either of the openings *i* and *k* is well over the port *e* when that one of the openings *h* and *l* leading to the same chamber is about to enter upon the corresponding one of the ports *c* and *d*, substantially as shown and specified. 40

3. A valve consisting of two parts, one of said parts corresponding to a **D**-valve, and the other of said parts corresponding to a **B**-valve, the edges of passages and ports presenting projections and grooves, to provide 45 one or more passages across the plane of contact of valve and valve-seat of an irregular or zigzag shape, as set forth.

4. A valve, being a combination of a **D**-valve and a **B**-valve, the openings in that part 50 of which that corresponds to a **B**-valve and the ports in the seat therefor are located in such relation to each other that when the opening leading from either of the two chambers is well over the common exhaust-port in the 55 seat the port leading from the seat to the same chamber in the valve is about to be opened, substantially as and for the purpose set forth.

HENRY F. SHAW.
